TOY AEROPLANE

Nevilles E. Walker, Portland, Oreg.

Application April 3, 1931, Serial No. 527,454

7 Claims. (Cl. 46—50)

My invention relates to aeroplanes and glider construction and primarily to small types used as toys. Because of the fact that the only type of motor sufficiently light and inexpensive and adapted to propel said toy planes is one made of a rubber band, said toys have limited flying ability. It is necessary, further, that the body be made of extremely light construction, either of wood such as balsa, or of oiled silk or paper.

10 The object of my invention is to provide a plane of this character, which is susceptible of flying a reasonable distance relatively and yet one which is capable of being formed to correspond closely to the contour and structure of standard planes.

15 I accomplish this result by forming the body of a single stick of balsa wood turned to tapered form leaving only a sufficient shell to obtain substantial rigidity. The forward, larger diameter end is capped by an element closely encircling said body,

20 binding it to prevent distortion and breakage, said cap further forming the mounting for the propeller shaft for such plane. Extending into the rear end of said plane is a removable clip arranged adjacent the tail skid, which with the 25 end of the propelling shaft form the connecting elements to which the ends of the elastic motor are secured. The intermediate portions of said band motor are housed within the hollow body substantially along the median line of the latter.

30 The wing element is arranged to pass below such motor, not only to provide clearance, but also to provide lateral and longitudinal stability, in that it becomes possible to introduce a substantial dihedral angle in the wing and still keep the line 35 of resistance relatively low.

The body walls are arranged to yieldingly hold such wing element, because of the fact that the wing element is given curved contour and the slots thru the walls of the body are lineal. The 40 distortion of the wings produced by forcibly arranging them in the wall slots yieldingly holds the wing element fixed in position when subjected only to normal flight conditions, but yields to prevent breakage when the wing strikes a solid 45 object in flight, because the slots are substantially longer than the wing element to accommodate movement.

The details of construction and operation are hereinafter described with reference to the 50 accompanying drawing, in which:

Fig. 1 is a longitudinal section thru said toy aeroplane;

Fig. 2 is a transverse section looking forward thru the wing; and

55 Fig. 3 is a perspective view of such plane.

My improved plane comprises a body *a* extending longitudinally of the plane and comprises a single integral element, tubular in section and tapered longitudinally. The forward end of the body terminates in a forwardly extending circular flange of relatively large diameter with respect to the body of the plane and the rearward end terminates virtually in a point *a*2. The latter end is slotted and holds the elements *b*, *b*' and *b*2 forming the tail structure. The element *b* extends vertically and the elements *b*' and *b*2 extend outwardly at opposite sides and all of such parts are of like shape. At the forward end two angularly disposed truss-shaped braces *c* carry wheels *c*' and form the landing gear for the 70 plane, such wheels being mounted upon laterally extending axles *c*2.

Upon the upper portion of the body, I preferably provide an opening *d*, above which a piece of transparent material *d*' and a stream line block 75 *d*2 are carried to simulate a cockpit.

The walls of said body are extremely thin to secure light weight and said body is preferably made of wood such as balsa wood. The latter wood lacks strength and to prevent the body 80 from being crushed easily, a cap *e* is provided, which cap is preferably made of a heavier section than the body. Such cap fits tightly over and seals the forwardly extending flange *a*', the bounding flange *e*' fitting tightly over the flange 85 *a*'. The body and cap being annular in section, the latter thus serves to resist distortion, because of such tight fit and thus compressive strains upon such body are resisted by the bounding action of said cap.

90 The flanges *e*' and *a*' respectively are provided with a tongue *e*2 and a groove *a*3, which engage each other to prevent rotation of such parts. An inwardly projecting boss *e*3 is formed upon such cap and is arranged to extend centrally towards the tubular body. A propeller *f* is carried by the face of said cap upon a propelling shaft *g*. Such shaft receives bearing support from such cap by extending thru the boss *e*3, which is preferably provided with a metallic cap *e*4 upon its inner face. The propeller is spaced from the head by a semi-spherical spacer *f*' and the inner end of the propeller shaft *g* is formed into an eye *g*'.

105 A tail skid piece *h* is arranged at the rear pointed end of the body *a* and beneath the tail structure elements *b*' and *b*2. A piece *i* of the body is made removable and the forward end is tapered so that the piece will be wedged in place. A clip *j* is secured to the piece *i*. An eye *j*' is formed at one end of the clip, said eye extending into the 110

hollow body to a point substantially upon the median line of such body. An elastic motor element *k* extends longitudinally of the body and is fastened at one end to the eye *g*' formed upon the inner end of the propeller shaft *g* and is fastened at the other end to the eye *j*' of the clip *j* and thus extends substantially the full length of the body.

Said elastic motor element preferably comprises one or more lengths of rubber, inasmuch as its action is substantially noiseless and such material is inexpensive and easily procured. Thus the propeller is driven by securing distortion in said elastic motor element, which when 10 winding in one direction upon release will rotate the propeller oppositely and the plane will be driven thru the air. The clip *j* is free and removable with the piece *i*, so that the end of the elastic secured thereby may be removed with 15 such piece to provide means for joining such end to a mechanical winding device. The other end of such rubber band also is removable for the same purpose, the cap and piece both being held in place by the pull of the elastic motor element 20 longitudinally of the plane.

In aeroplanes of this character, it is relatively easy to secure good gliding ability with a symmetrical plane. That is, one which will glide well under uniform motion, as when released 25 from a point at rest and permitted to fall downwardly. When such devices are provided with a forwardly-arranged propeller, the latter tends to pull the plane upwardly until it moves into a vertical stall. This results in flights of limited 30 duration and erratic motion in the air, dissimilar to flights of standard aeroplanes. On the other hand it is relatively simple to provide a nose-heavy miniature plane, which is capable of sustained horizontal flight under full motor power. 35 When such power is exhausted at the end of its travel, the plane being nose-heavy dives for the earth and ends nose-on, not only tending to break the parts, but also to provide a landing which is 40 not similar to one had with standard flying conditions.

A plane such as the one shown in the drawing is symmetrical about a vertical plane and has good gliding ability and lateral stability. Good lateral stability is accentuated by a relatively large degree 45 of dihedral offset in the wing element. Thus the center of gravity is at a point adjacent the median line of the body or slightly below. The dihedral angle of the wings causes the center of resistance to forward motion to be at a point substantially 50 spaced above such center of gravity. The thrust line of the propeller normally extends along a line coincident with the median line of the body and thus such thrust line is substantially lower than the center of resistance thus producing a 55 compound force tending to cause the plane to nose upwardly. I have discovered that if the angle of the propeller shaft is changed so that it is directed upwardly towards the rear of the plane and extends thru the center of resistance, then, in that 60 event, the plane will fly smoothly and along a horizontal plane, or with reasonable upward climb. That is, if the thrust line extends substantially thru the center of resistance, such compound tipping force is eliminated and good flight 65 conditions are maintained. These theoretical lines and centers are shown graphically in Fig. 1.

Said graphic showing thus discloses that the line of resistance extends above the median line of the body and below the plane of the tips of the 70 wing, the dihedral angle of said wing causing the

tips to extend to a plane substantially above the body as is shown in Fig. 1. The thrust line extends thru the axis of rotation of the propeller and makes an oblique angle with the line of resistance. The line of resistance is parallel to the line of flight and to the median line of the body, but said line of resistance does not coincide with said median line, the band motor *k* extending substantially along said median line. The center of resistance thus is that point on the line of resistance where the resisting factors forward of said point offset and balance those factors lying aft of said point.

To secure increased lift, the wing element 1 is given camber. Said wing, to secure economy and to aid in its mounting, is preferably made of uniform thickness. The slits *m* extending thru the body walls are preferably lineal, or formed upon a curvature different than the arc given the wings to produce such camber. The wings are distorted, that is, flattened in the specific device illustrated, so that they may pass thru said lineal slots. Such wing elements are distortable and are elastic and thus tend to resume their horizontal curved form, which tending binds them tightly in said slots. Said slots are of substantially greater length than the width of the wing and thus said wing is permitted to yield when struck relatively by a solid, as in flight or in landing conditions, thereby to minimize breakage.

I claim:

1. In a toy aeroplane of the character described provided with a longitudinal body and a single lateral wing element, said aeroplane being symmetrical about a longitudinal vertical plane and having gliding stability and a propeller arranged at the forward end of said body and mounted upon a longitudinal axis extending along a line obliquely intersecting the line of resistance and passing substantially thru the center of resistance of said aeroplane.

2. In a toy aeroplane of the character described provided with a longitudinal body and a single lateral wing element, said aeroplane being symmetrical about a longitudinal vertical plane and having gliding stability, and having its center of resistance substantially above its center of gravity and a propeller arranged at the forward end of said body and mounted upon a longitudinal axis extending along a line obliquely intersecting the line of resistance and passing substantially thru the center of resistance of said aeroplane.

3. In a toy aeroplane of the character described provided with a longitudinal body and a single lateral wing element, said aeroplane being symmetrical about a longitudinal vertical plane and having gliding stability, said wing element provided with a substantial percentage of dihedral offset resulting in the aeroplane having its center of resistance substantially above its center of gravity and a propeller arranged at the forward end of said body and mounted upon a longitudinal axis extending along a line obliquely intersecting the line of resistance and passing substantially thru the center of resistance of said aeroplane.

4. In an aeroplane of the character described provided with a longitudinal body and a transverse wing element carried thereby, said wing element comprising one continuous element of uniform thickness and curved laterally to provide said wing element with camber, a slot formed in the side wall of said body for receiving and holding said wing element, said slot being of

- different shape than the cross-section of said wing, the latter being elastic and distortable, whereby seating said wing in said slot under pressure to distort the latter binds said wing element yieldably in said slot, the elasticity of said wing being sufficient to cause the portions thereof spaced from said slot to resume their normal curved section. 5. In an aeroplane of the character described provided with a longitudinal body and a transverse wing element carried thereby, said wing element comprising one continuous element of uniform thickness and curved laterally to provide such wing element with camber, a linear slot formed in the side wall of said body for receiving and constituting the sole means for holding said wing element, said slot being of different shape than the cross-section of said wing, the latter being elastic and distortable, whereby seating said wing in said slot under pressure to distort the latter binds said wing element yieldably in said slot, the elasticity of said wing being sufficient to cause the portions thereof spaced from said slot to resume their normal curved section. 6. In an aeroplane of the character described provided with a longitudinal body and a transverse wing element carried thereby, said body being hollow, slots formed in the side walls of said hollow body for receiving and holding said wing element, said slots being of different shape than the cross-section of said wing, the latter being elastic and distortable, whereby seating said wing in said slots under pressure to distort the latter binds said wing element yieldably in said slots, the elasticity of said wing being sufficient to cause the portion thereof spaced from said slot to resume their undistorted section respectively.
- than the cross-section of said wing, the latter being elastic and distortable, whereby seating said wing in said slots under pressure to distort the latter frictionally binds said wing element yieldably in said slots, the elasticity of said wing being sufficient to cause the portions thereof spaced from said slot to resume their undistorted section respectively.
7. In an aeroplane of the character described provided with a longitudinal body and a transverse wing element carried thereby, said body being hollow and annular in section, and of substantial diameter at the point of connection with said wing element, said wing element comprising one continuous element of uniform thickness and curved laterally to provide such wing element with camber, linear slots formed in the side walls of said hollow body for receiving and frictionally holding said wing element, said slots being of substantially greater length than the width of said wing element, said slots being of different shape than the cross-section of said wing, the latter being elastic and distortable, whereby seating said wing in said slots under pressure to distort the latter binds said wing element yieldably in said slots, the elasticity of said wing being sufficient to cause the portion thereof spaced from said slot to resume their undistorted section respectively.
